UNITED STATES PATENT OFFICE.

FREDERICK WESTERBECK, OF ST. LOUIS, MISSOURI.

SHEET-METAL CAN.

1,083,574.

Specification of Letters Patent.

Patented Jan. 6, 1914.

Application filed April 10, 1911. Serial No. 620,134.

To all whom it may concern:

Be it known that I, FREDERICK WESTERBECK, a citizen of the United States of America, residing at the city of St. Louis, in the 5 State of Missouri, have invented certain new and useful Improvements in Sheet-Metal Cans, of which the following is a full, clear, and exact description, reference being had to the accompanying drawings, forming 10 a part of this specification.

My invention relates to that type of sheet metal can which is provided with a cover having a seamless neck formed with a seamless bead onto which the flange of a closure 15 is crimped to close the mouth of the can neck.

My invention consists in a sheet metal can of the type referred to which comprises a cover formed with a seamless neck which 20 is provided at its outer end with an outwardly jutting bead, and also with an inwardly inclined downwardly extending seamless flange, and having combined therewith a closure cap which contacts with said 25 inturned flange of the neck, and which extends downwardly to a point slightly above the bottom of the flange of said neck; the cap being also provided with an outwardly extending annular flange which is crimped 30 about and beneath the outwardly jutting bead at the outer end of the neck whereby said cap is securely held to the bead and the depressed central portion of the cap retained in fixed contact with the inwardly inclined, downwardly extending seamless 35 flange of the neck, as hereinafter described and claimed.

In the accompanying drawings: Figure I is a top or plan view of my sheet metal can 40 cover and closure. Fig. II is in part an elevation and in part a vertical section of my cover and closure applied to a sheet metal can body. Fig. III is an enlarged section through the neck of the cover and 45 closure.

A designates the body of a can and B the can cover, the latter being provided with a seamless neck C. The can cover and its neck are made from a single sheet of metal 50 which is drawn into the shape shown by a series of drawing actions similar to those ordinarily carried out in producing sheet metal articles of irregular contour. The can cover is separate from the body A and

may be secured thereto in any suitable manner. 55

The neck C of my can is provided at its mouth end with a seamless bead 1, formed by bending the metal in the neck outwardly in a slight curve relative to the plane of the body of the neck and then inwardly over the neck from the jutting portion and downwardly toward the upper end of the neck and spaced therefrom, with the result of producing an internal seamless flange 2 60 that is slightly inclined inwardly toward the center of the neck, and the free edge of which is spaced away from the interior face of the neck wall. It will furthermore be seen that the bead 1 of my cover neck may 65 be produced without any excessive drawing action such as would cause a fracture of the metal. It is also to be emphasized that only slight bending and drawing action of the metal is necessary to produce the 70 straight internal flange 2; hence there is no liability of a fracture in this flange starting from its free end and extending therefrom into the bead to render the latter unfit to perform its duty in conjunction with the 75 cap closure.

3 designates the closure cap, which is of the same form as that usually employed on beaded cover necks of the type hereinbefore referred to, and for which no invention *per 80 se* is herein claimed. The closure cap has a depressed central portion, beneath which the flange 2 extends slightly so that the diameter of the opening at the bottom of the flange is slightly less than the diameter of the bottom of the closure cap, a slightly flaring rim 90 or annular wall 4, and an outer annular flange 5, concentric with the rim 4 and crimped about and beneath the bead 1 of the neck of my cover. 95

It is worthy of notice that the internal flange 2 acts as a reinforcement for the outer portion of the bead 1 to which the annular flange of the closure cap is crimped and that when the crimping action is carried out, the bead 100 with the internal flange 2 considered in part as an integral portion of the bead becomes wedged between the annular flange and annular wall 4 of the closure cap to effect a most secure joint between the closure cap and the 105 cover, and hence removing all possible opportunity for leakage through such joint. It is therefore readily apparent that the en-

gagement of the edge of the annular flange 5 with the contracted part of the cover at or near the base of the bead 1 will securely hold the closure cap in position and against displacement.

1 claim:

10 A sheet metal can comprising a cover formed with a seamless neck provided at its outer end with an outwardly jutting head, and an inturned inwardly inclined downwardly extending seamless flange, and a clo-

sure cap contacting with said inturned flange and extending downwardly to a point slightly above the bottom of said flange, said cap being provided with an outwardly extending securing flange crimped about and beneath the outwardly jutting bead at the outer end of the neck. 15

FREDERICK WESTERBECK.

E. B. Linn.

Correction in Letters Patent No. 1,083,574.

It is hereby certified that in Letters Patent No. 1,083,574, granted January 6, 1914, upon the application of Frederick Westerbeck, of St. Louis, Missouri, for an improvement in "Sheet-Metal Cans," an error appears in the printed specification requiring correction as follows: Page 2, line 9, for the word "head" read *bead*; and that the said Letters Patent should be read with this correction therein that the same may conform to the record of the case in the Patent Office.

Signed and sealed this 10th day of February, A. D., 1914.
